UNITED STATES PATENT OFFICE.

AP TREVOR JONES, OF CHICAGO, ILLINOIS, ASSIGNOR TO AMERICAN STEEL FOUNDRIES, OF CHICAGO, ILLINOIS, A CORPORATION OF NEW JERSEY.

STOCKLESS ANCHOR.

Application filed April 15, 1922. Serial No. 553,078.

To all whom it may concern:

Be it known that I, AP TREVOR JONES, a citizen of the United States, residing at Chicago, in the county of Cook and State of Illinois, have invented certain new and useful Improvements in a Stockless Anchor, of which the following is a specification.

This invention relates to stockless anchors and is an improvement upon the arrangement disclosed in my Patent No. 1,373,740, granted April 5, 1921.

One object of the invention is to provide a stockless anchor in which the shank may be automatically locked to the head for causing a quick gripping action of the flukes into the bottom of the sea, and also in which the shank may be automatically and positively unlocked from the head as the anchor is raised from a gripping or holding position.

Another object is to provide a simple and efficient means for preventing the locking members from assuming an abnormal position.

Another object is to provide a stockless anchor adapted to meet the various requirements for successful use.

These and other objects are accomplished by means of the arrangement disclosed on the accompanying sheet of drawings, in which—

Figure 1 is a front elevation of an anchor embodying my invention;

Figure 2 is a side elevation of the same anchor;

Figure 3 is a fragmentary side elevation of the same anchor, a portion of the head being in section and showing the shank in a vertical position with the flukes at an angle of forty-five degrees with respect thereto, one of the two positions taken by the parts of the anchor as the latter is being lowered and raised; and

Figure 4 is a side elevation of the same anchor, a portion of the head being shown in section and showing the shank locked to the head of the anchor for causing a quick gripping action of the anchor when passed into engagement with the bottom of the sea,

the position shown being that which is assumed after the head of the anchor has reached the bottom of the sea and the shank having moved downwardly a certain predetermined amount from its vertical position.

The various novel features of the invention will be apparent from the following description and drawings, and will be particularly pointed out in the appended claims.

Referring to the figures of the drawings, it will be noted that I have shown a stockless type of anchor including a head 10 and a shank 11, the latter being pivotally connected to the former by means of trunnions 12 extending laterally from the shank and cooperating with bearing portions within the head. The inclined walls 13 of the head form stops for limiting the relative movement between the shank 11 and head 10. Preferably the maximum relative movement between said parts is about ninety (90) degrees, there being a forty-five (45) degree swinging movement to either side of a centrally aligned position of the head and shank. However, it will be noted, reference being had particularly to Figure 4, that when the head and shank are in locked position such parts are at an angle of thirty-five (35) degrees with respect to each other, the remaining ten (10) degrees being effective in facilitating the positive unlocking of the shank from the head in a manner to be referred to in detail hereinafter.

The head 10 is provided with two flukes 14 which are the ground engaging or gripping members. The head is also provided with oppositely and laterally extending projections 15 at the base of the flukes to cause the latter to assume a digging or gripping position when the head of the anchor rests upon the bottom of the sea, as shown in Figure 4.

The stockless type of anchor in itself, without special provision being made, is a little slow in digging into and gripping the bottom of the sea in spite of the inclination given to the flukes by the projections 15, as shown in Figure 4. To overcome this

disadvantageous feature and to cause a quicker gripping action of the flukes of the anchor, means have been provided whereby the shank of the anchor will become 5 locked with respect to the head thereof at the proper point so that the weight of the shank, together with the weight of at least a portion of the chain, will act in a manner to increase the digging or gripping action 10 of the flukes of the anchor.

As shown in Figure 4 of the drawings, the shank 11 of the anchor is locked to the head 10 thereof by one of two locking members 16 having a hooked portion 17 which is 15 in locking engagement with a shoulder 18 formed on the head of the anchor. The locking members 16 are pivotally connected on opposite sides of the shank 11 on a pin 19 extending through the shank and through 20 the members 16. Said locking members preferably are independently movable with respect to each other and each is provided with a weighted portion 20 for holding the hooked portion 17 in a position to hook 25 over and remain in hooked relationship with the shoulder 18 as the shank swings downwardly from a vertical position to the position shown in Figure 4, and also for assisting the locking member 16 to move out of 30 locking engagement with the shoulder of the head when the shank 11 is moved toward a vertical position from that shown in Figure 4. With the parts as shown in Figure 4, the shank 11 is prevented from moving 35 downwardly relative to the head of the anchor, the weight of the shank and also the weight of the chain 21, or at least a portion thereof, and its clevis member 22 connecting it to the shank 11, act in a manner to cause 40 a relatively quick gripping and hooking action of the flukes into the bottom of the sea, this being especially true in view of the fact that the weight of the shank 11, clevis 22 and chain 21 act through a relatively long 45 lever arm. It will be understood that the shank 11 may be locked to the other side of the head by the associated curved actuated locking member 16 in a manner similar to that shown in Figure 4 of the 50 drawings.

Reference being had particularly to Figure 4, it will be noted that the head 10 adjacent the shoulders 18 is provided with 55 recesses 23 and that one wall 24 of each of said recesses is curved or cam shaped to have a cam-like action on the hooked portion 17 of the associated locking member 16 for positively lifting the hooked portion 17 out of engagement with the shoulder 18 as 60 the shank 11 is raised from the position shown in Figure 4. It will be noted that each cam surface 24 extends to a point beyond the outer edge of the associated shoulder 18 for positively insuring a complete 65 unlocking movement of the locking

member 16 with respect to the head. The hooked portion 17 of the locking member 16 is permitted to have a riding movement on the associated cam surface 24 by virtue of the clearance between the inner stop wall 13 70 of the head and the associated side of the shank 11. A further advantage is provided by means of the arrangement shown, in that if the hooked portion 17 should fail to pass down into locking engagement with the 75 shoulder 18 upon a downward movement of the shank, it would be necessary only to raise the shank slightly without lifting the head or the flukes of the anchor preparatory to a second attempt to lock the parts together. 80

Each locking member 16 is provided with a laterally extending projection 25 adapted to engage the shank 11 for limiting the relative movement of one with respect to the other and more particularly to prevent the locking members from turning over or assuming abnormal positions from which they could not automatically be returned for proper functioning. 90

It is my intention to cover all modifications of the invention falling within the spirit and scope of the following claims.

I claim:

1. A stockless anchor including a head, a shank movably connected thereto, means for locking said head and shank in a given relative position for creating a gripping leverage, causing a quick gripping action of the anchor, and means for giving the locking 100 means a positive unlocking movement for unlocking said head and shank. 95

2. A stockless anchor including a head, a shank movably connected thereto, means for locking said head and shank in a given relative position for creating a gripping leverage, causing a quick gripping action of the anchor, and means for positively unlocking 105 said head and shank. 105

3. A stockless anchor including a head, a shank movably connected thereto, means for locking said head and shank in a given relative position for creating a gripping leverage, causing a quick gripping action of the anchor, and cam means for positively un- 110 locking said head and shank. 115

4. A stockless anchor including a head, a shank movably connected thereto, a pivotally mounted locking member carried by said shank and having a portion adapted to engage the head for locking the shank and head in a given predetermined relative position, and means for positively moving the locking member out of locking engagement for releasing said head and shank. 120

5. A stockless anchor including a head provided with a locking shoulder and a guide portion associated therewith, a shank movably connected to the head, and a locking member carried by said shank and mov- 125 130

able into engagement with said shoulder for locking said head and shank, said locking member being positively moved out of locking position by said guide portion.

5 6. A stockless anchor including a head, a shank pivotally connected thereto, means for locking said head and shank in a given relative position when the shank has moved

from a vertical position a predetermined amount, and means for positively unlocking 10 said head and shank when the shank has moved toward a vertical position from a locked position.

Signed at Chicago, Illinois, this 8th day of April, 1922.

AP TREVOR JONES.
